UNITED STATES PATENT OFFICE.

JOHN T. APPLEBERG, OF BALTIMORE, MARYLAND.

ADVERTISING MATCH-BOX.

SPECIFICATION forming part of Letters Patent No. 283,741, dated August 28, 1883.

Application filed March 13, 1883. (No model.)

To all whom it may concern:

Be it known that I, JOHN T. APPLEBERG, of Baltimore, in the county of Baltimore and State of Maryland, have invented certain new and useful Improvements in Advertising Match-Boxes; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of the box closed. Fig. 2 is a similar view, showing it open. Fig. 3 is a vertical cross-section, and Fig. 4 is a vertical longitudinal section of the box closed.

Similar letters of reference indicate corresponding parts in all the figures.

My invention has relation to boxes for containing matches, more particularly the class of matches known as "safety-matches," in which the match can be ignited only by striking it against a chemically-prepared surface; and it consists in the improved construction of the box, as hereinafter more fully described and claimed, whereby the same may be used as an advertising medium.

In the accompanying drawings, A represents the body of the box, which is rectangular in shape, and by preference is made of thin wood or shavings; or pasteboard may be used, if desired. By reference to Fig. 3 it will be seen that the box is made by folding the blank at the corners *a* of the box, the blank being made of sufficient length to leave an extra flap for a cover, (shown at B,) which should be a trifle longer than those parts of the blank which form the box proper, so as to project endwise from the same, as shown at *b* in Fig. 4. Inserted into the box thus formed, and which, it will be seen, has open ends, is a sliding box or drawer, C, which contains the matches. The cover B is fastened to the end pieces of the sliding drawer C by means of small pieces of paper, (shown at *d*,) and which, if desired, may be in one piece with the label, which is pasted on the

top of the cover, the free ends of these paper lapels being pasted to the end pieces of the sliding box, so as to hold the same firmly in place. To open the box these lapels are cut or torn where they join the projecting ends of the cover, which may readily be effected, 55 owing to the projections *b b*.

Upon the inside of the cover B a suitable advertisement may be placed, extending over the fixed top of the box, so as to be concealed from view when the cover B is folded 60 down upon the fixed top of the box, A'. When, however, the paper fastenings *d d* are cut for the purpose of opening the box, the cover B will spring open, thus exhibiting the advertisement on the inside. In handling 65 the boxes by the trade these, it will be seen, have all the appearances of ordinary match-boxes, there being nothing to distinguish them from the same, so that the advertisement contained in or on the box can form no objection; but the moment the box is opened by 70 the consumer the advertisement will be displayed in a conspicuous manner, and will remain so displayed as long as the box is in use. Inasmuch as the box itself is necessary, 75 in order to use the matches, which can only be ignited by striking them upon the chemically-prepared surface on the sides *e e* of the same, the box will not be thrown away, as is often the case with boxes containing friction-matches of the ordinary kind, but will 80 be retained as long as any of its contents are left.

Having thus described my invention, I claim and desire to secure by Letters Patent of the 85 United States—

1. An advertising match-box, A, having a cover, B, adapted to fold upon the fixed top A' of the box, and the sliding drawer C, the fixed top of the box and the inside of the cover 90 being adapted for the display of advertisements, substantially as and for the purpose shown and set forth.
2. An advertising match-box, A, having open ends and a fixed top, A', the sliding 95 drawer C, adapted to contain the matches, and the cover B, hinged to one corner of the box, said cover having ends *b b* overlapping

the body of the box and secured thereto by fastenings *d d*, and adapted for the display of advertisements on the inside of the cover B and fixed top A' of the box, substantially as and for the purpose shown and set forth.

In testimony that I claim the foregoing as

my own I have hereunto affixed my signature in presence of two witnesses.
